UNITED STATES PATENT OFFICE.

BRUNO V. NORDBERG, OF MILWAUKEE, WISCONSIN.

VARIABLE-CAPACITY COMPRESSOR.

No. 900,418.

Specification of Letters Patent.

Patented Oct. 6, 1908.

Application filed September 8, 1903. Serial No. 172,368.

To all whom it may concern:

Be it known that I, BRUNO V. NORDBERG, a citizen of the United States, residing at Milwaukee, in the county of Milwaukee and State of Wisconsin, have invented certain new and useful Improvements in Variable-Capacity Compressors, of which the following is a specification, reference being had to the accompanying drawing, forming a part thereof.

The object of this invention is to provide means for varying the quantity of air delivered by an air compressor running at a constant speed. Under some constructions this has been accomplished either by throttling the whole quantity of air before it entered the compressor, thereby reducing its density, or by unloading the compressor; that is, either by establishing communication between the interior of the cylinder and the atmosphere, or by establishing communication between the opposite ends of the cylinder, or by stopping the delivery of air altogether. The first method is objectionable because by throttling the air the work of compressing is increased above that necessary to compress the same volume of air from atmospheric pressure to the required pressure. The second method is objectionable because the whole load of the compressor is put on or thrown off, thereby subjecting the motor to extreme variations of load, and since in most cases either electric motors or water wheels are employed to operate the compressors, this mode of regulation is very unsatisfactory.

According to the present invention the load is increased or decreased exactly in proportion to the demand for air, the compressor running at a constant speed.

The invention consists in certain novel features of construction and in the peculiar arrangement and combinations of parts hereinafter particularly described and defined in the claims.

In the accompanying drawing like characters designate the same parts in the several figures.

Figure 1 is a side elevation of a compressor embodying the invention; Fig. 2 is a pressure diagram illustrating its operation; Fig. 3 is an enlarged vertical longitudinal section of one end of the cylinder, including one set of valves, which are duplicated at the other end of the cylinder; Fig. 4 is a vertical sec-

tion of the regulator for automatically varying the point of tripping and closing the inlet valves; and Fig. 5 is a detail view on an enlarged scale of automatic valve gear suitable for the purpose.

Referring to Figs. 1 and 3, *a* is the compressor cylinder, *b* the piston, *c* one of the inlet valves, which are preferably of the semi-rotative Corliss type, and *d* one of the discharge valves, which are of the self-acting puppet type, designed to open whenever the pressure in the cylinder equals or slightly exceeds that in the discharge chest, and to close when there is an excess of pressure in the discharge chest. The inlet valves may be operated by any suitable form of Corliss valve gear which can be adapted to release and close said inlet valves during any portion of the suction stroke of the piston, the valves being set so that they will open when the piston commences its suction stroke, or a little later, and will be positively closed at the end of such stroke. Valve gear like or similar to that shown and described in United States Letters Patent No. 680,667, granted to me August 13, 1901, may be used for the purpose, and I have shown and will briefly describe such valve gear. As the inlet valve operating mechanism is the same at both ends of the cylinder, it will be sufficient to describe in detail that at one end only.

Referring to Fig. 5 in connection with Fig. 1, *e* is the valve closing arm fixed on the stem of each valve *c* and connected by a rod *f* with the piston of a dash pot *g*. *h* is the valve opening arm, loosely mounted on the stem of the valve and movable independently of the arm *e*. *i* is the trip cam pivoted to the arm *h*, and *j* is the trip arm, which is also pivoted to the arm *h*, and has a crank pin engaging with said cam. *k* and *l* are the latch blocks attached to the closing arm *e* and the trip arm *j* respectively. *m* is a wrist lever mounted on the cylinder and connected by rods with the opening arm *h*. It is also connected by a rod with a rocker arm *n*, which is in turn connected by a rod and strap with an eccentric *o* on the crank shaft *p*.

The automatic regulator which determines the point of tripping and closing the inlet valves, consists generally as shown in Fig. 4 in connection with Fig. 1, of a cylinder *q* mounted in a vertical position on the compressor frame, a plunger *r* fitted in the lower end of this cylinder, a weighted sleeve *s* fitted

and movable vertically on the cylinder *q*, a spring *t* interposed between the plunger *r* and the upper end of said sleeve, and a device for checking or retarding the movement of said sleeve. This checking or retarding device consists in the present case of a dash pot *u*, fixed to the upper end of the sleeve *s*, and a plunger *v*, fixed to a stand *w* on the compressor frame. The sleeve *s* is adjustably weighted by divided rings *x*, to determine the pressure which the compressor is to maintain, and it constitutes a weight for determining said pressure. The cylinder *q* is connected below the plunger *r* with the discharge chest of the compressor or the reservoir into which it delivers compressed air, by a pipe *y*. The sleeve *s* is connected by crank arms engaging a groove therein, with a rocker shaft *z*, supported by the stand *w*. One arm of a T-lever *2*, suspended by a bar *3* from the shaft *z*, is connected by a rod *4* with a corresponding arm *5* on said shaft *z*. The other two arms of said lever *2* are connected by rods with the trip cams *i*. The bar *3* is connected by a rod with a rocker arm *6*, which is in turn connected by a rod and strap with an eccentric *7* on the crank shaft *p*. The eccentric *o* through the rocker arm *n* and wrist lever *m*, vibrates the valve opening arms *h* through a constant arc, and opens the inlet valve *c* at or near the beginning of the suction strokes of the piston, if the cams *i* are in position to permit the engagement of the trip blocks *k* and *l*. The valves *c* are also positively closed at the ends of the suction strokes of the piston by the action of the arms *h* engaging on their return movement with the arms *e*, in case the dash pots fail to promptly act. The times or points of tripping and closing the inlet valves *c* relative to the suction strokes of the piston are determined by the regulator, which through the connections hereinbefore described, moves the cams *i* into positions to disengage the trip blocks *k* and *l* sooner or later, according to the pressure exerted on plunger *r*. An increase of pressure causes said trip blocks to be disengaged and the inlet valves to close earlier, while a decrease of pressure in like manner causes said valves to close later.

The operation of the compressor hereinbefore described may be explained as follows: Assuming that the regulator plunger *r* is in a position to release the inlet valves *c* at the middle of the stroke of the piston *b*, as said piston makes the first half of its suction stroke, air is admitted into the cylinder through the open inlet valve *c*, this part of the stroke being indicated on the pressure diagram Fig. 2, by the line 8—9. Point 9 indicates the middle of the stroke of the piston at which the open inlet valve is tripped and is suddenly closed. The air supply to the cylinder is thus cut off and the volume already admitted is confined therein, so that

the further movement of the piston in the same direction causes this air to expand, as indicated by line 9—10, 10 indicating the end of the stroke at which the piston is reversed and commences its compression stroke. When the piston is at point 10 of its stroke there is a vacuum in the cylinder, indicated by the line 10—11 on the diagram; that is, the whole volume of air admitted to the cylinder through the open inlet valve, as indicated by line 8—9, has now been expanded to a volume indicated by the line 8—11, and instead of being at atmospheric pressure it is now at a reduced pressure indicated by the distance 10—11 below the atmospheric line 8—11. As the piston upon its return movement makes its compression stroke, the air is compressed as indicated by the curved line 10—12. At point 12 the pressure in the cylinder equals or slightly exceeds that in the discharge chest, the automatic discharge valve *d* towards which the piston moves opens, and air is delivered into the discharge chest during that part of the stroke of the piston indicated by the line 12—13.

It will be obvious that if the release and closure of the inlet valve had not occurred at the point 9, as indicated on the diagram, but said valve had remained open during the entire stroke 8—11, the compression line would have then corresponded with the line 11—14, and the volume of air delivered would be indicated by the line 14—13. It is also obvious that if the inlet valve had been tripped and closed earlier in the stroke, a smaller volume of air would have been delivered by the compressor; while if said valve had been tripped and closed later, a larger volume of air would have been delivered.

If there were no heating and cooling of the air during the compression and expansion periods, the expansion line 9—10 would coincide with the lower part of the compression line 10—12, but as the air is cooled by expansion during this operation, heat is imparted to it by the walls of the cylinder, and as its temperature is not raised by compression to that of the cylinder until the compression reaches a point say, 15, on the diagram, it absorbs heat from the cylinder up to this point, and there is consequently a slight discrepancy between the expansion curve 9—10 and the lower part of the compression curve 10—12, as indicated by the shaded portion of the diagram. This is practically the only loss in efficiency due to the means and method herein shown and described, of varying the capacity of the compressor.

Various changes in the details of construction and arrangement of parts may be made without materially affecting the operation of the compressor and without departing from the principle and intended scope of the invention.

I claim:

1. In a variable capacity compressor the combination with the compressor cylinder and piston and suction and discharge valves, of automatic valve releasing and operating gear constructed and arranged to release and positively close the suction valve at different points in the suction stroke of the piston according to the varying demand on the compressor, said gear operating to advance the time of closing the suction valve to reduce the compression and being directly controlled in its action by pressure from the compressor while the compressor runs at a constant speed, substantially as described.
2. In a variable capacity compressor the combination with the cylinder, piston and suction and discharge valves, of automatic valve releasing and operating gear constructed and arranged to release and positively close the suction valve at different points in the suction stroke of the piston and to keep said valve closed during the compression stroke of said piston, said gear operating to advance the time of closing the suction valve to reduce the compression and being directly controlled in its action by pressure from the compressor while the compressor runs at a constant speed, substantially as described.
3. In a variable capacity compressor the combination with a cylinder and piston, of a self acting discharge valve, a positively actuated suction valve and automatic valve releasing and operating gear constructed and arranged to release and close the suction valve at different points in the suction stroke of the piston, said gear operating to advance the time of closing the suction valve to reduce the compression and being directly controlled in its action by pressure from the compressor, whereby the volume of air or gas compressed on the return stroke is varied according to the varying demand on the compressor while the compressor runs at a constant speed, substantially as described.
4. In a variable capacity compressor the combination with the compressor cylinder having suction and discharge valves, of automatic valve releasing and operating gear constructed and arranged to release and close the suction valve at different points in the suction stroke of the compressor, said gear operating to advance the time of closing the suction valve to reduce the compression and a pressure regulator comprising an expansion chamber having a movable part which is connected with the releasing mechanism of said valve gear and is actuated by pressure from the compressor while the compressor runs at a constant speed, substantially as described.
5. In a variable capacity compressor the combination with the compressor piston and a cylinder having suction and discharge valves, of automatic valve releasing and

operating gear constructed and arranged to release and close the suction valve at different points in the suction stroke of the piston, and a pressure regulator comprising an expansion chamber having a movable part, a weight connected with the releasing mechanism of said valve gear, and a spring or elastic connection between said movable part and weight, the movable part of said pressure regulator being actuated by pressure from the compressor to vary the volume of air admitted to the compressor cylinder while the compressor runs at a constant speed, substantially as described.

6. In a variable capacity compressor the combination with the compressor piston and a cylinder having suction and discharge valves, of automatic valve releasing and operating gear comprising a trip cam and constructed and arranged to release and close the suction valve at different points in the suction stroke of the piston, and a pressure regulator comprising an expansion chamber having a movable part, means connecting said movable part with the trip cam, and a spring and adjustable weight forming a part of the connection between said movable part and trip cam, the movable part of said pressure regulator being actuated by pressure from the compressor to vary the volume of air admitted to the compressor cylinder while the compressor runs at a constant speed, substantially as described.

7. In a variable capacity compressor the combination with the compressor piston and a cylinder having self acting discharge valves and suction valves, of automatic valve releasing and operating gear having trip cams and constructed and arranged to release and close the suction valves at different points in the suction stroke of the piston and to keep said valves closed during the compression stroke, whereby the volume of air or gas compressed on the return stroke is varied according to the varying demand on the compressor, and an automatic pressure regulator comprising an expansion chamber having a fluid pressure supply connection, a movable part, means connecting said movable part with the trip cams and a spring, weight and check or retarding device forming a part of the connection between said movable part and trip cams, the movable part of said pressure regulator being actuated by pressure from the compressor to vary the volume of air admitted to the compressor cylinder while the compressor runs at a constant speed, substantially as described.

8. In a variable capacity compressor the combination with the compressor cylinder and piston and suction and discharge valves, of automatic valve gear constructed and arranged to positively close the suction valve at any point in the suction stroke of the pis-

ton, said valve remaining closed during the entire compression stroke of the piston, and an automatic regulator actuated by variations in pressure produced by the compressor and operating directly upon the valve gear while the compressor runs at a constant speed to vary the volume of air admitted to the compressor cylinder from the full cylinder capacity to zero, according to

the varying demand on the compressor, substantially as described.

In witness whereof, I hereto affix my signature in presence of two witnesses.
